OIL-COOLING RADIATOR

Rex B. Beisel, West Hartford, Conn., assignor to
 United Aircraft Corporation, East Hartford,
 Conn., a corporation of Delaware

Application July 13, 1935, Serial No. 31,253

12 Claims. (Cl. 123—196)

This invention relates to improvements in oil cooling radiators for engines and has for an object the provision of an improved oil cooling radiator for an internal combustion engine and particularly an aircraft engine. A further object resides in an improved mounting for such an oil cooling radiator so that the radiator will not add any material drag to the airplane.

Other objects and advantages will appear as the description proceeds.

The accompanying drawings forming a part of this application illustrate a suitable mechanical embodiment of what is now considered to be the preferred form of the invention; the drawings, however, are for the purpose of illustration only and are not to be taken as limiting the invention, the scope of which is to be measured entirely by the scope of the appended claims.

In the drawings, Fig. 1 is a front elevational view of a fragmentary portion of an engine showing an oil cooling radiator constructed according to the idea of this invention mounted thereon. Fig. 2 is a transverse sectional view on an enlarged scale on the line 2—2 of Fig. 1. Fig. 3 is a detail view of the door actuating means illustrated in Fig. 2 at the bottom of the radiator. Fig. 4 is a front elevational view on an enlarged scale of the oil cooling radiator showing a fragmentary portion of the engine upon which the radiator is mounted.

Referring to the drawings in detail, the numeral 10 generally indicates an internal combustion engine having a crankcase 12 upon which are mounted a plurality of radially disposed cylinders, 14, to form a radial engine of a type commonly employed as power plants for airplanes. The engine is provided with a cooling system comprising air cooling baffles as indicated at 16 arranged one between each two adjoining cylinders and shaped to conform closely to the exterior profile of the cylinders to provide a restricted air passage around the cylinder cooling surfaces, and head baffles 18 to provide a restricted passage around the cooling surfaces of the cylinder rocker arm boxes 20 and 22. The entire engine is preferably enclosed in a stream-lined cowling 24, and the baffles 16 and 18, together with the engine 10, form a partition extending transversely across the interior of the cowling 24 to provide within the cowling a high air pressure portion forward of the engine, and a low air pressure portion rearward of the engine so that the cooling air will flow past the cooling surfaces of the engine at a high velocity and thereby efficiently remove the excess heat from the engine.

For a more complete description of this baffle and cowling construction reference may be had to the patent of A. L. MacClain, #2,031,541 issued February 18, 1936 for Engine cooling system, filed July 8, 1932.

Prior to this invention it has been the common practice to mount an oil cooling radiator somewhere upon the exterior of the airplane or the engine cowling, usually in the slip stream of the airplane propeller, so that air currents induced by the propeller or by the forward motion of the airplane when in flight would cause air to flow through the radiator to carry away excess heat of the engine lubricating oil. Such a mounting adds materially to the drag forces on the airplane and such additional drag forces are present whether the oil cooling radiator is being used or not. This invention contemplates mounting the oil cooling radiator so that it is disposed entirely within the circumference of the engine and therefore does not add appreciably to the drag forces tending to retard the progress of the airplane upon which it is mounted. Such a mounting is desirably accomplished by providing in one of the inter-cylinder baffles 16, an opening of a size and configuration to receive the oil cooling radiator therein. Preferably, but not necessarily, the oil cooling radiator is mounted in one of the upper inter-cylinder baffles such as the baffle between the top cylinder and the adjacent left hand cylinder as viewed in Fig. 1. As the space between the radially disposed cylinders of a radial type engine is restricted, particularly in width, the oil cooling radiator forming a part of this invention has been especially designed to fit into this restricted space and still provide ample cooling area for the transfer of heat from the oil passing therethrough. This is accomplished by providing an elongated, narrow radiator having a depth sufficient to provide within the radiator core, ample cooling surface regardless of the restricted face area of the core, and by providing two separate oil tanks comprising an inlet tank located at one end of the elongated core and an outlet tank located at the opposite end thereof.

In accordance with the above described objects, I have provided an oil cooling radiator having a relatively narrow elongated core 26, composed of a plurality of thin-walled tubes placed side by side, spaced apart a sufficient distance for the oil to circulate between them and sealed together at their ends, thus forming what is commonly known as a cartridge type radiator core. This core has secured to one end thereof, an oil inlet tank 28, and to the opposite end thereof an oil outlet

tank 30, and is mounted in a shell comprising side members 32 and 34, and end members 36 and 38, the side members being straight and conforming closely to the elongated sides of the core and the end members being rounded, or dome shaped, to conform to the shape of the tanks 28 and 30. For convenience in description, the portion of the radiator adjacent to the crankcase 12, as illustrated in Figs. 1 and 4, will hereinafter be referred to as the bottom of the radiator, and the portion adjacent to the rocker arm boxes will be referred to as the top of the radiator. The bottom end portion 36 is preferably made integral with, or rigidly secured to, the side members 32 and 34, and the top end portion 38 is made separate from the remainder of the shell and secured thereto by adjustable fastening elements as indicated at 40 and 41. A piece of resilient material 42, is disposed between the bottom tank 30 and the bottom portion 36 of the shell and a similar piece of resilient material 44 is disposed between the top tank 28 and the top 38 of the shell. Adjustment of the adjustable fasteners or screws 40 and 41 to draw the top member 38 and the respective side members 32 and 34 together will obviously place the pieces of resilient material 42 and 44 in compression and thereby securely retain the core 26 in the shell. The side members 32 and 34 are each provided with outwardly extending flanges as indicated at 46 and 48 in Fig. 2, and 46 in Fig. 4, the flange 46 preferably overlying the portion of the baffle 16 surrounding the opening provided therein to receive the radiator, to provide a substantially air-tight seal between the oil cooling radiator and the baffle. At their upper ends these side members 32 and 34 are provided with outwardly extending transverse flanges 50 through which the adjustable screws 40 and 41 extend, the shell top 38 being provided with cooperating flanges 52 overlying the flanges 50 to provide a support for the upper ends of the screws. At the upper end thereof the shell is secured to the engine by means of a pair of brackets 54 and 56, the bracket 54 having one end attached to the engine by the nut 58 of the rocker arm bearing extending through the rocker arm box 20, and its opposite end secured to the shell by means of the screw 40 which also serves to secure the shell top 38 to the remainder of the shell. The bracket 56 upon the opposite side of the shell from the bracket 54, has one end thereof secured to the engine by means of the nut 60 of the rocker arm bearing extending through the rocker arm box 22, and has its other end secured to the shell by means of the screw 41 which secures the shell top 38 to the shell side member 34. An additional bracket member 62 may be attached to the radiator shell by suitable means such as one of the adjustable connection screws as indicated at 41 and secured to some part of one of the adjacent engine cylinders as by a screw 63 tapped into the cylinder head. This bracket is desirably mounted in such a manner as to add to the fore and aft stability of the radiator. At the bottom thereof the shell is secured to the crankcase 12 of the engine by means of a pair of brackets 64 and 66, the bracket 64 being connected to the side member 34 by suitable means such as the rivet 68 and having a pair of legs 70 and 72 extending downwardly from the side member for engagement with the crankcase 12 and, if desired for attachment to the cylinder hold down bolts 74 by means of which the cylinders are secured to the crankcase of the engine. The bracket 66 is similarly secured to the side member 32 and

may be attached to the engine by means of the hold down bolts of the engine cylinder adjacent thereto. This construction obviously provides a simple and efficient means for rigidly and securely mounting the oil cooling radiator on the engine between two adjacent cylinders thereof so that the radiator can not be displaced from the engine by the force of the air stream passing therethrough, or by the engine vibration and by means of which the radiator core will be to some extent cushioned against the vibrational effects of the engine. 10

As explained above, the baffle 16 is a part of an air pressure partition providing the interior of the cowling 24 with a high air pressure portion 15 and a low air pressure portion so that, the placing of the oil cooling radiator in the baffle between the high and low pressure portions insures a flow of cooling air through the radiator whenever the cooling effect of the radiator is needed. As the 20 air passage openings through the radiator core are relatively restricted in area, the effect of the oil cooling radiator upon this air pressure differential is ordinarily not sufficiently serious to require that any special means be provided to 25 overcome the same. If, however, the engine upon which the oil cooling radiator is mounted were operating under extremely adverse cooling condition, it might be desirable to protect the pressure differential upon the opposite sides of the air 30 pressure partition from the adverse effect produced by the oil cooling radiator. This object may be suitably attained by providing at the rear of the radiator a separate air passage opening 35 through the cowling to the exterior thereof. However, as the pressure differential and incident cooling of the engine may be controlled over a wide range by adjustment of the cowl trailing edge flaps 78 such a radiator vent would ordinarily be unnecessary. 40

There are certain times during the operation of the engine when the lubricating oil has a sufficiently low temperature for best operating conditions and the cooling thereof provided by the radiator is not necessary or desirable. As the air 45 passing through the radiator by reason of its friction and turbulence will place a slight drag upon the airplane even when the radiator is mounted within the engine disc, it is desirable that even this slight effect may be eliminated when the 50 cooling effect of the oil radiator is not needed and therefore, in order to discontinue the cooling effect of the radiator when it is not necessary or desirable and at the same time to eliminate all of the drag forces incident to the use of the oil cooling radiator, I have provided upon the front face of the radiator a pair of doors or shutters as indicated at 80 and 82 which, when closed as illustrated in Fig. 1, prevent the passage of air through the radiator core and thus render the baffle 16 60 substantially impervious to the passage of air therethrough. The doors 80 and 82 are hinged to the core 26 along the forward edges thereof, and extend in length for substantially the entire length of the core 26 and in width substantially 65 to the center line of the core. A rod 84 is secured to the door 80 by suitable means such as the rivets 86, parallel to and adjacent to its hinge and a similar rod 88 is secured to the door 82, both of these rods projecting below the lower ends of the 70 doors as clearly illustrated in Fig. 4. Upon the lower ends of the rods 84 and 88 are crank arms 90 and 92 respectively, secured to the rods against rotation relative thereto and, between the free ends of the crank arms 90 and 92 there is dis- 75

posed a toggle linkage comprising a pair of link members 94 and 96 pivotally secured to the arms 90 and 92 respectively and pivotally secured together by a pivotal connection 98 at their adjoining ends. These links 94 and 96 extend rearwardly from the arms 90 and 92 to the pivotal connection 98 so that a forward movement of the connection 98 will move the forward ends of the arms 90 and 92 in a direction to rotate the rods 84 and 10 88 in a direction to open the doors 80 and 82, as clearly illustrated in Fig. 3. A manually actuatable member in the form of a push and pull rod 100 is secured at one end to the pivotal connection 98 and slidably extends through a guide bracket 102 and rearwardly to a location within reach of the operator of the airplane so that axial movement of the rod 100 will serve to open or 15 close the doors 80 and 82 of the radiator.

As the spaces between the tubular members of 20 the radiator core are greatly restricted to force the oil within the radiator into thin streams for efficient cooling, when the oil is cold and viscous it will not flow readily through the radiator core. In order to provide for a sufficient flow of lubricating oil when the engine is first started and the oil is cold, and to avoid any dangerous pressures in the oil lines or cooling radiator, I have provided between the radiator inlet 104 and the radiator outlet 106 a pressure relief valve generally 25 indicated at 108. This relief valve comprises a bypass conduit 110 leading from the radiator inlet to the radiator outlet and provided with a valve seat 112. A valve plunger 114 is carried by a casting 30 116 which forms an extension of the bypass conduit 110 beyond the radiator outlet 106, and a coiled compression spring 118 by which the plunger is urged to closing position. The spring 118 has a resistance sufficient to maintain the valve closed and cause the oil to circulate through 35 the cooling radiator when the oil is warm but will permit the valve to open to bypass the radiator when the oil is too viscous to flow through the confined spaces provided in the radiator core.

The radiator is preferably so positioned relative to the engine that its center line lies substantially in the plane of the center lines of the engine cylinders and so that it extends substantially the entire length of the space between the two adjoining cylinders between which it is 40 mounted to thus effect the utmost use of the limited space available without in any way infringing upon the space surrounding the engine which will be desired for other purpose or projecting beyond the engine disc.

While I have illustrated and described a special 45 mechanical embodiment of the idea of my invention, it is to be understood that the invention is not limited to the specific construction so illustrated and described, but that such changes in 50 the size, shape, and arrangement of parts may be resorted to as come within the scope of the subjoined claims.

Having now described my invention so that others skilled in the art may clearly understand 55 the same, what I desire to secure by Letters Patent is as follows:

1. In combination with an engine having a plurality of cylinders cooled by an air blast, and a series of baffles for confining said air blast to the 60 cooling surfaces of said engine, an oil cooling radiator positioned between and fixedly secured to two adjacent cylinders, the baffle between said cylinders surrounding said radiator and directing air therethrough.

2. In combination with an engine having a

plurality of cylinders cooled by an air blast, and a series of baffles for confining said air blast to the cooling surfaces of said engine, an oil cooling radiator in one of said baffles positioned between two adjacent cylinders, and means for regulating the flow of air through said engine and said radiator.

3. In combination with an engine having a centrally disposed crankcase, a plurality of radially disposed cylinders around said crankcase, 10 a cowl surrounding said engine, and an air pressure baffle between each two adjacent cylinders, an oil radiator in one of said air pressure baffles, means securing said baffles and said radiator to said cylinders, and means supporting said radiator on said crankcase.

4. In combination with an engine having a centrally disposed crankcase, a plurality of radially disposed cylinders around said crankcase, and an air pressure baffle between each two adjacent 20 cylinders, an oil radiator for said engine having a drag reducing mounting in an opening in one of said baffles, doors hinged to close said opening, and manually operable means for closing said doors when the cooling effect of said radiator is 25 not needed to thereby entirely eliminate the drag of said radiator.

5. In combination with an engine having a plurality of cylinders cooled by an air blast, a 30 cowl surrounding said engine and a baffle between each two adjacent cylinders to form with said cylinders an air pressure partition in said cowl having a high air pressure space on one side thereof and a low air pressure space on the opposite side thereof, an oil cooling radiator having 35 a perforate core to permit the passage of air therethrough mounted in an opening in said partition between said high air pressure space and said low air pressure space to provide a more efficient cooling effect for said radiator while at 40 the same time substantially eliminating the drag thereof.

6. In combination with an engine having a plurality of cylinders cooled by an air blast, a 45 cowling surrounding said engine, and a baffle between each two adjacent cylinders of said engine to form with said engine a partition to divide the interior of said cowling into a high air pressure portion and a low air pressure portion, an oil cooling radiator having a perforate core to permit 50 the passage of air therethrough mounted in an opening in said partition between said high air pressure portion and said low air pressure portion.

7. In combination with an engine having a 55 centrally disposed crankcase, an open ended cowl surrounding said engine and projecting forwardly and rearwardly thereof, a plurality of radially disposed cylinders around said crankcase, and an air pressure baffle between each two adjacent 60 cylinders to form with said engine a partition in said cowl to restrict the flow of air from the forward end to the rearward end of said cowl to provide within said cowl a high pressure chamber and a low pressure chamber, and an oil cooling radiator having a perforate core to permit 65 the passage of air therethrough mounted in an opening in one of said baffles, and disposed between said chambers.

8. In combination with an engine having a 70 plurality of cylinders cooled by an air blast, a cowling surrounding said engine, and a baffle between each two adjacent cylinders of said engine to form with said engine a partition to divide the interior of said cowling into a high air 75

pressure portion and a low air pressure portion, an oil cooling radiator having a perforate core to permit the passage of air therethrough mounted in an opening in said partition, an oil inlet and oil outlet for said radiator, and a pressure relief valve between said inlet and said outlet to bypass said radiator when the oil is viscous.

9. An oil cooling radiator for an engine comprising, a cartridge type core, a two part shell surrounding said core, resilient material between said core and said shell, an adjustable connection between the two parts of said shell for compressing said resilient material, and brackets for securing said shell to said engine.

10. An oil radiator for an engine comprising, an elongated cartridge type core, a shell surrounding said core and secured to said engine, a pair of doors extending lengthwise of said core hinged to said shell at opposite sides thereof, a rod secured to each door and projecting beyond one end thereof, a toggle linkage connected to the projecting ends of said rods, and a manually actuatable member connected to said toggle linkage to open and close said doors.

11. In a high speed vehicle having an engine surrounded by a drag reducing cowl and a plurality of air pressure baffles within said cowl be-

tween the cylinders of said engine, and a radiator for cooling the lubricating oil of said engine, the arrangement for further reducing the drag of said vehicle which comprises, mounting said oil cooling radiator in one of said baffles so that the 5 frontal area of said radiator lies wholly within the extent of the frontal area of said engine.

12. In a high speed vehicle having an engine surrounded by a drag reducing cowl, a plurality of air pressure baffles within said cowl between 10 the cylinders of said engine, and a series of adjustable flaps at the trailing edge of said cowl for controlling the flow of cooling air past said baffled engine, and a radiator for cooling the lubricating oil of said engine, the arrangement 15 for further reducing the drag of said vehicle and rendering the cooling effect of said oil cooling radiator directly responsive to the cooling requirements of said engine which comprises, mounting said oil cooling radiator in one of said 20 air pressure baffles so that the frontal area of said radiator is wholly within the extent of the cross sectional area of said cowl and the flow of air through said radiator is under the control of said adjustable cowl flaps.

REX B. BEISEL.
